UNITED STATES PATENT OFFICE.

MICHAEL A. DONOHUE, JR., OF CHICAGO, ILLINOIS.

DESIGN FOR A SCHOOL-DESK CASTING.

SPECIFICATION forming part of Design No. 36,005, dated August 12, 1902.

Application filed May 22, 1902. Serial No. 108,606. Term of patent 7 years.

To all whom it may concern:

Be it known that I, MICHAEL A. DONOHUE, Jr., a citizen of the United States, residing at Chicago, in the county of Cook and State of Illinois, have invented and produced a new, original, and ornamental Design for School-Desk Castings, of which the following is a specification, reference being had to the drawing forming a part thereof.

10 In the accompanying drawing the figure is a view showing in side elevation a casting embodying my ornamental design.

As shown in the drawing, the leading or material features of my design lie in the configuration and ornamentation of said casting.

15 The lower end of the casting is composed of the two feet 1 and 2, connected by a curving frame portion 3. Another curving marginal frame portion 4 rises from the foot 2 and has

20 near its upper end a circular portion 5. From the circular portion 5 the marginal frame portion 6 is quite sharply reentrant and at its upper end is extended upwardly in the ribbed marginal frame portion 7, which latter connects with the similarly-ribbed top frame portion 8, extending substantially at right angles with the ribbed marginal portion 7. The marginal frame portion 9 extends in a forward curve upward from the foot 1, curving

25 rearward at its upper end and turning slightly downward at its upper extremity. The marginal frame portion 9 is connected with the reentrant marginal portion 6 by the integral ribs 10 and 11, forming a panel 12 upon the

30 side of the casting. A straight (and nearly horizontal) bar 13 connects the upper end of the marginal portion 9 with the upwardly-extending ribbed marginal portion 7, and the rear end of this bar is connected with the rear

35 end of the ribbed upper marginal portion 8 by means of the ogee scroll portion 14. The upper edge of the upper ribbed marginal portion 8 and the forward edge of the similarly-ribbed marginal portion 7 are provided

with button-like projections of inverted-cone 45 form.

The body of the casting is divided into three spaces A, B, and C, traversed by vine-like scrolls. The scrolls 15 and 16, that lie within the spaces A and B, rise as one stem 50 in the angle formed between the marginal portion 9 and the straight bar-like portion 13. Said scroll 15 turns upward and passing behind the bar 13 turns rearward within the space A, forming a letter S, two of the leaves 55 or subbranches of the scroll turning forward within the space A and one of said leaves or subbranches larger than the others making a spiral within the lower loop of the letter S. This spiral is joined with the main branch by 60 two leaves or subbranches. The upper portion of the letter turns upon itself and terminates in a spreading leaf.

The lower branch 16 of the scroll or vine extends downward within the space B, its 65 branches following the outline portion 9 for some distance, extending to the opposite side of the space B and touching the ribbed outline portion 7, thence returning again to the outline portion 9. An upwardly-curving leaf 70 or subbranch fills the upper part of the space B, and in the center of the curve of this subbranch a flower 17 is placed.

The scroll 18 arises in the angle formed between the curved marginal portions 3 and 4 75 and describes an ogee curve in the space C. A branch of said scroll or vine turns forward from the stem and lies in a curve in the space C, and the extremity of said vine curves forward in a scroll and is divided at its end. 80

I claim as my invention—

The ornamental design for a school-desk casting, substantially as herein shown and described.

MICHAEL A. DONOHUE, JR.
